UNITED STATES PATENT OFFICE.

WILLIAM BAXTER GLISSON, OF RUTHERFORD, TENNESSEE.

CHART.

No. 801,781.

Specification of Letters Patent.

Patented Oct. 10, 1905.

Application filed April 27, 1905. Serial No. 257,708.

To all whom it may concern:

Be it known that I, WILLIAM BAXTER GLISSON, a citizen of the United States, residing at Rutherford, in the county of Gibson and State 5 of Tennessee, have invented certain new and useful Improvements in Charts; and I do hereby declare the following to be a full, clear, and exact description of the invention, such as will enable others skilled in the art to which 10 it appertains to make and use the same.

My invention relates to charts, and more particularly to adjustable holders therefor.

The object of the invention is to provide a chart-holding frame having means whereby a 15 chart of considerable length can be rolled and unrolled and kept taut during such operation.

Another object is to provide means for holding the chart at a desired inclination.

With the above and other objects in view 20 the invention consists of a supporting-stand upon which is rotatably mounted a stem projecting downward from a frame containing oppositely-disposed rollers. A chart in the form of a flexible strip is secured at opposite 25 ends to these rollers and is adapted to be wound thereon and then unwound therefrom. Means are provided for simultaneously rotating the rollers and also for tightening the strip upon the rollers, so as to prevent it from 30 sagging.

The invention also consists of the further novel constructions and combinations of parts hereinafter more fully described, and pointed out in the claims.

35 In the accompanying drawings I have shown the preferred form of my invention.

In said drawings, Figure 1 is a perspective view of my improved chart-holder, a portion thereof being broken away, but indicated by 40 dotted lines. Fig. 2 is a central vertical section through the holder and showing a chart therein, and Fig. 3 is an enlarged section through the spring-pressed drive-sprocket.

Referring to the figures by numerals of reference, 1 1 are standards which support a head 2, having a centrally-disposed aperture 3, surrounded by a raised portion 4, constituting a bearing. The standards 1 are braced at a point below the head 2 by means of a connection 5, having a slot 6 therein and a depending loop 7. The bearing 4 supports a preferably rectangular casing 8, having its lower portion enlarged transversely, as shown at 9, and its upper portion similarly enlarged, as 55 shown at 10. Between these enlargements and the opposite ends of the frame are remov-

able panels 11, adapted to be secured in any suitable manner, as by means of buttons 12. Within the extension 9 is mounted a roller 13, to which is secured one end of a chart 14 in 60 the form of a flexible strip. This chart extends under a cross-rod 15, secured within the frame adjacent roller 13, and the other end of the chart is fastened to a roller 16, which is arranged within the enlargement 10. A 65 sprocket 17 is disposed outside of the frame and is secured to and rotates with roller 16, and mounted on this sprocket is a chain 18, which extends around a sprocket 19, rotatably mounted on the shaft 20 of roller 13. The inner face of sprocket 19 is provided with shallow recesses adapted to receive pins 21, extending from the shaft 20, and the sprocket is held normally in engagement with these pins by means of a coiled spring 22, which bears at 75 opposite ends upon rings 23 and 24, located on shaft 20. The ring 24, as shown in Fig. 3, is preferably integral with the sprocket 19. A crank 25 is connected to the end of shaft 20. A stem 26 projects downward from the 80 center of frame 8 and is rotatably mounted in the opening 3 and slot 6. This stem is secured to frame 8 by means of a metal strap 27, which is secured to opposite sides of the stem and to the bottom of the frame and terminates in a bracing-strap 28, as shown in Fig. 1, said bracing-strap being secured to one side of the frame. That portion of the strap below the stem 26 forms a loop 29, to which is pivoted an angular strip 30, having 85 one end of a locking-strip 31 pivoted to it. This locking-strip has a series of notches 32, any one of which is adapted to receive the yoke 7, and a handle 33 extends from the locking-strip, so that the same can be readily manipulated.

It will be understood that by raising and pulling forward the locking-strip 31 stem 26 can be swung in the opening 3, thereby causing the frame 8 to assume an inclined position. 90 It can be locked by replacing strip 31 in engagement with loop 7. Roller 13 can be rotated in either direction by means of crank 25, and rotary motion will be transmitted to roller 16 through chain 18. The chart 14 can 95 therefore be unrolled from one of the rollers and rolled on the other. Should it be desired to tighten the chart upon the rollers, so as to prevent it from sagging, a hook 34, which is pivoted to the frame 8, may be placed in engagement with chain 18, so as to prevent movement thereof. Then by turning shaft 20 the 100

105

110

same will rotate within the sprocket 19, and thereby cause the lower roller to rotate independently of the upper one and take up any sag. This independent movement of the shaft 5 and sprocket 19 is permitted because of the fact that the sprocket is locked to the shaft by the spring 22, which presses it against the pins 21. When sufficient pressure is exerted, however, the pins will force the sprocket laterally and permit of independent movement. It will of course be understood that either or 10 both of the panels 11 can be removed to permit the examination of the chart.

Having thus fully described my invention, 15 what I claim as new, and desire to secure by Letters Patent, is—

1. In a device of the character described the combination with a support, of a chart-holding frame mounted thereon; a stem depending from the frame and rotatably mounted within the support, said stem being also capable of swinging in the support, means for manipulating the stem and a securing device therefor.
2. In a device of the character described the combination with a support; of a chart-holding frame mounted thereon and having

its opposite faces removable, a stem depending from the frame and rotatably mounted within the support, said stem being also capable of swinging in the support, a lever pivotally connected to the stem, and a holding-loop normally engaged by the lever.

3. In a device of the character described the combination with a support; of a chart-holding frame mounted thereon and having its opposite faces removable, the opposite ends of the frame being enlarged to accommodate a rolled chart, a stem depending from the frame and rotatably mounted within the support, said stem being also capable of swinging in the support, a strap secured upon opposite faces of the stem and to the bottom of the frame for holding the stem and frame together, a manipulating device pivoted to the strap, and means for securing said device in adjusted position.

In testimony whereof I have signed my name to this specification in the presence of two subscribing witnesses.

WILLIAM BAXTER GLISSON.
